(57) **CLAIM**

The ornamental design for a metal detector with active magnetic sensor technology as shown and described.

DESCRIPTION

The patent or application file contains at least one drawing executed in color. Copies of this patent or patent application publication with color drawing(s) will be provided by the Office upon request and payment of the necessary fee.

1. Metal detector with active magnetic sensor technology

1.1 : Perspective

1.2 : Perspective

1.3 : Right

1.4 : Left

1.5 : Top

1.6 : Bottom

1.7 : Front

1.8 : Back

The device is used to detect underground metals and natural gold particles; the device has an ergonomic infrastructure allowing the user to detect metal in the most effective way.
